UNITED STATES PATENT OFFICE.

LEONIDAS L. TITTLE, JR., OF DAYTON, OHIO.

CLOTHES-PIN.

1,265,139.

Specification of Letters Patent.

Patented May 7, 1918.

Application filed November 16, 1915. Serial No. 61,824.

To all whom it may concern:

Be it known that I, LEONIDAS L. TITTLE, Jr., a citizen of the United States, residing at Dayton, in the county of Montgomery and State of Ohio, have invented certain new and useful Improvements in Clothes-Pins, of which the following is a specification.

My invention relates to clothes pins and the primary object thereof resides in the provision of a device of this character embodying novel means for retaining an article on a line, novel guiding means being also provided for facilitating the application of the pin about an article which is on the clothes line.

Another object of this invention resides in the provision of a novel lug on one of the clamping arms for coöperation with the other of the clamping arms in retaining an article on a line and reducing the accidental displacement of the article from the line to a minimum.

A further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

In the drawings:—

Figure 1 is an end elevational view of my improved pin illustrating to advantage the construction of the looped clamping arm;

Fig. 2 is a side elevational view of my invention; while

Fig. 3 represents a perspective view of my invention for holding an article on a clothes line, two pins being shown to illustrate the construction and arrangement of the arms when they are applied.

Referring more particularly to the drawings in which similar reference numerals designate like and corresponding parts throughout the different views, I provide a clothes pin formed from a single piece of wire, that is preferably galvanized to prevent rust from accumulating on the articles of clothes when they are hung on the line.

In forming the clothes pin, I have bent the wire intermediate its ends to provide a coil

1 which has a spring action, the said coil having a resilient clamping arm 2 and a resilient clamping arm 3 extending therefrom. The arm 2 is longer than the arm 3 and bent 60 as indicated by the numeral 4 in a plane at right angles to the plane of the coil 1 and then bent upon itself to provide a substantially oval-shaped loop 5. The other arm is arranged in spaced parallel relation with the 65 plane of the looped arm 5 and substantially intermediate the sides of the loop, the lower end of which arm is bent toward and arranged slightly within the plane of the looped arm to provide a retaining lug 6. 70 The extreme free end of this arm which continues from the lug is extended outwardly at an acute angle with respect to the arm to provide a guide 7 which is arranged in substantially divergent relation to the 75 guide 8 provided by bending the looped end outwardly as illustrated to advantage in Fig. 2 of the accompanying drawings.

The operation of this invention is as follows:

Assuming that it is desired to clamp an article of clothes on a line, the coil 1 is engaged by one hand to the guides 7 and 8 arranged upon the article of clothes when the article is on the line. When in this position, 85 by exerting a downward pressure on the pin, the arms 2 and 3 will be forced away from each other and the pin will be slid downwardly until the coil is arranged about the clothes engaging the line. When in this 90 position, the spring action of the coil on the resilient clamping arms, causes the lug 6 to extend slightly within the plane of the looped arm 2, pressing the article of clothes between the loop and consequently preventing 95 accidental displacement of the clothes from the line. The guides 7 and 8, especially the former, are elongated, so as to reduce the tearing of clothes to a minimum, when using the pin.

Although I have shown and described the preferred embodiment of my invention, I desire it to be understood that I am not to be limited to the exact details shown, however, I desire that great stress be laid upon 105 the arrangement and the coöperation between the arms extending from the coil as well as the guiding means on the arms.

From the above description taken in connection with the accompanying drawings, it 110 can be easily seen that I have provided a device that is simple in construction, con-

taining but a few simple parts that can be cheaply manufactured and assembled and when assembled can be placed upon the market and sold at a minimum cost.

5 It will be understood that the above description and accompanying drawings comprehend only the general embodiment of my invention and that various minor changes in detail of construction, proportion, and 10 arrangement of parts may be made within the scope of the appended claims and without sacrificing any of the advantages of my invention.

Having thus fully described my invention, 15 what I claim as new and desire to secure by Letters Patent, is:

1. A clothes pin comprising a single piece of wire formed intermediate its ends with a resilient butt-joint open ring having substantially parallel clamping arms extending from the ends of the ring, an ovoidally shaped loop formed on one of the arms, a lug formed on and adjacent one end of the other arm, said lug being adapted to normally extend slightly within the plane of the loop to coöperate with the said loop for clamping an article therebetween, and presenting diverging guides formed on the arms for facilitating the application of the 30 pin to a clothes line, said clothes line being adapted to pass between the arms of the pin

and to normally lie within the ring when the pin is applied thereto, said ring further being adapted to encircle an article looped over the clothes line.

2. As a new article of manufacture, a clothes pin formed of a single piece of resilient wire with a split ring intermediate its ends serving as a clothes-line engaging and supporting portion and from which extend arms, one of said arms having a portion thereof recurved to form a loop turned at right angles to the split ring so that the axis of the loop is in the same plane as the ring, the other arm extending approximately parallel to the loop and having its free end formed with a projection that normally lies within the loop, said split ring being adapted to encircle and engage with an article looped over a clothes line while the arms clamp another portion of the article therebetween, said ring further serving as a support for retaining the pin in an operative relation to the line and against accidental displacement.

55 In testimony whereof I affix my signature in presence of two witnesses.

LEONIDAS L. TITTLE, JR.
